Patented Sept. 1, 1959

186,026

FURNITURE LEG

Robert H. Monroe, East Orange, N.J., and Marvin K. Culbreth, Wilton, Conn., assignors to Molla Incorporated, Westbury, N.Y., a corporation of New York

Application November 21, 1957, Serial No. 48,599

Term of patent 14 years

(Cl. D33—14)

FIG. 1

FIG. 2

FIG. 3

FIG. 4

Fig. 1 is a side elevational view of a furniture leg showing our design, the view looking in the direction of the arrow 1 of Fig. 3.

Fig. 2 is a front elevational view.

Fig. 3 is a top plan view on an enlarged scale; and

Fig. 4 is an enlarged view in cross-section taken along the line 4—4 of Fig. 2.

We claim:

The ornamental design for a furniture leg, as shown.
